UNITED STATES PATENT OFFICE.

THOMAS GAQUIN, JR., AND WILBUR F. NOTT, OF HAVERHILL, MASSACHUSETTS, ASSIGNORS OF TWO-FIFTHS TO MYRON A. NICHOLS, OF SAME PLACE.

RUBBING-IN MACHINE FOR BOOTS OR SHOES.

SPECIFICATION forming part of Letters Patent No. 442,250, dated December 9, 1890.

Application filed June 26, 1890. Serial No. 356,917. (No model.)

To all whom it may concern:

Be it known that we, THOMAS GAQUIN, Jr., and WILBUR F. NOTT, both of Haverhill, in the county of Essex, State of Massachusetts, have invented certain new and useful Improvements in Rubbing-In Machines for Boots or Shoes, of which the following is a description sufficiently full, clear, and exact to enable any person skilled in the art or science to which said invention appertains to make and use the same, reference being had to the accompanying drawings, forming part of this specification, in which—

Figure 1 is an elevation of our improved machine; Fig. 2, a top plan view of the same, and Fig. 3 an elevation showing certain details of construction.

Like letters of reference indicate corresponding parts in the different figures of the drawings.

Our invention relates to a machine for rubbing the stain or finishing color into the soles of boots or shoes; and it consists in certain novel features hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the body of the machine, which consists of a rectangular frame. A horizontally-arranged shaft *b* is journaled centrally in the ends of the frame and bears a fixed pulley *d* and loose pulley *f* and a beveled gear *g*. A vertical stub-shaft *h* is journaled in the top *i* of the frame and bears a beveled gear *j*, meshing with the gear *g* on the main shaft. A sector-shaped crank is mounted on the upper end of the stub-shaft. An arm *p* projects laterally from one end of the frame-top *i*, and a lever *q* is pivoted by an end to said frame, the free end of said lever working in a slotted guide *r* at the opposite side of said top. A rod *B* is pivoted by one end at *t* to the small end of the sector *m*, and centrally at *v* to the lever *q*. The head *x* of said rod is offset vertically at *z*, and is

grooved on its under face longitudinally at *y* 50 (see Fig. 3) to form ways for receiving a rubbing-brush *C*. A thumb-screw *k* passes through the top of the head in engagement with said brush and secures it in said ways.

In the use of our improvement, the shaft *b* 55 being rotated, sets in motion the stub-shaft *h* and crank *m*. A horizontal circular movement is thereby imparted to the brush *C* by the rod *B* pivoted to said crank, the line of said movement forming an oval. The stain 60 or coloring-matter is applied to the shoe-sole, and said sole held in contact with the brush *C*. Said brush passing continuously over the same portions of the sole rapidly rubs the stain into the leather. By means of the ways 65 *y* the brush *C* may be substituted by a polisher or other implement. By imparting an oval movement to the brush the short motion of said portion may be utilized at the shanks and narrow portions of the shoe-sole to great 70 advantage and prevent the stain from being spattered onto the edges of said soles. The lever *q* imparts rigidity and prevents vertical movement of the brush. Said lever also permits the brush to be driven through a longer 75 oval than when the rod *B* is slotted and working on a fixed pivot, thus rendering the device much more rapid in its operation on the sole.

Having thus explained our invention, what 80 we claim is—

1. In a rubbing-in machine, the combination of a body and driving-shaft, a stub-shaft geared to said driving-shaft, a crank on said stub-shaft, a horizontal lever pivoted to said body, a horizontal rod pivoted to said lever and crank, and a rubbing-brush mounted on the free end of said rod, substantially as described.

2. In a rubbing-in machine, the combination of the body and driving-shaft with a stub-shaft geared to said driving-shaft and bearing a crank, a lever pivoted to one end of said body, a guide for the free end of said lever, and a rod pivoted to said lever and crank and provided in its free end with ways for receiving a rubbing-brush, substantially as described.

3. In a rubbing-in machine, the combination of the body and driving-shaft, the stub-shaft geared to said driving-shaft, a crank on said stub-shaft, a lever pivoted on said body, 5 and a horizontally-arranged rod pivoted to said crank and lever, the head of said rod being offset vertically and provided with brushways, a rubber adjustably disposed in said ways, and means for securing said brush 10 therein, and a guide for the free end of said lever, substantially as described.
4. In a rubbing-in machine, the body A and shaft b, in combination with the stub-shaft h,

geared thereto, a crank on said stub-shaft, the lever q, pivoted on said body, the guide 15 r for said lever, the rod B, provided with the head x, having the ways y and pivoted to said crank and lever, the rubber C, mounted in said ways, and the screw k for securing said rubber therein, substantially as de- 20 scribed.
